Atty.

UNITED STATES PATENT OFFICE.

THOMAS DANIEL CARTER, OF CHICAGO, ILLINOIS.

SPRING-CLUTCH.

No. 896,699.

Specification of Letters Patent.

Patented Aug. 18, 1908.

Application filed February 23, 1907. Serial No. 359,022.

To all whom it may concern:

Be it known that I, THOMAS DANIEL CARTER, a citizen of the United States, residing at Chicago, in the county of Cook and State of Illinois, have invented a new and useful 5 Improvement in Spring-Clutches, of which the following is a complete specification.

This invention relates to improvements in spring clutches and more particularly to a 10 spring clutch having clamping members thereon adapted to support articles therebetween without danger of marring them.

It is frequently desirable to provide supports for bench tools or other articles of ordinary daily use in places of convenient access and it is the object of this invention to provide a spring clutch adapted to be attached to a wall or other convenient support and which is capable of gripping articles 15 20 which cannot ordinarily, because of their construction, be hung up.

It is a further object of this invention to provide a device capable of supporting articles in regard to which care must be taken to 25 prevent marring or injuring, such as umbrellas having expensive handles, and canes or other articles of ordinary use for which a convenient and safe support may be desired.

The invention consists of the matters hereinafter described in the specification and 30 more fully pointed out and defined in the appended claims.

In the drawings: the figure is a perspective view of a device embodying my invention.

35 As shown in said drawings: a back plate 1 is provided which may be of any desired material, preferably metal, and if preferred may have any ornamental design thereon to give it an artistic appearance. Said plate 40 as shown is of greater length than width and has its corners cut away, though the shape is immaterial, and is provided at each end with an aperture adapting it to be secured to a wall or other object forming its support. 45 Extending longitudinally of said plate and rigidly engaged thereto by riveting, or in any other preferred manner, is the strap 2, of metal, which is provided at its upper end with laterally directed arms 3. At the lower 50 end said strap is provided with an upturned hook 4, forming a support for such articles as it may be desired to hang thereon, such for instance as coat hangers. Said strap is bent outwardly from the plate at two points 55 intermediate its ends affording an offset por-

tion 5 which is thus raised a distance from the plate. Supported on the device thus formed is a spring clamp comprising a resilient wire formed at its center to provide a coil 6 which is loosely engaged beneath the offset portion 5 of the strap, and the ends of which extend outwardly or forwardly from the bottom of the coil and are turned upwardly and inwardly in approximately parallel relation with each other and which project forwardly from the plate a sufficient distance to clamp an article therebetween. The extreme ends 8 of said wire are brought into close proximity to the plate and secured to the arms 3 of the strap. If desired and as 60 65 shown the clamping members 7 may be provided with a soft, yielding covering 9 such as rubber tubing which acts to prevent marring articles held therebetween.

The operation is as follows: When the device is suspended on its support the coil 6 is loosely engaged beneath the strap so that it is free to expand or contract to permit articles of different sizes to be engaged between the clamping members. Owing to 70 the resiliency of the coil said members are permitted considerable lateral movement while each remains in a plane approximately at right angles to the plate thereby increasing its gripping effect. The hook at the bottom of the strap affords a convenient place on which to hang articles capable of being hung thereon. 85

I claim as my invention:

1. In a device of the class described the 90 combination with a strap having an offset portion thereon, of a resilient coil beneath said offset portion and clamping members integral with said coil and projecting forwardly of said strap. 95

2. In a device of the class described the combination with a strap, of a resilient coil on one side thereof, and clamping members integral with said coil and extending on the opposite side of the strap therefrom and connected to said strap. 100

3. In a device of the class described the combination with a back plate of a strap thereon, having an offset central portion, a coil loosely supported between said plate and offset portion and clamping members extending forwardly from said coil on either side of the strap and connected at their ends to said strap. 105

4. In a device of the class described the 110

combination with a back plate of a strap thereon having a central offset portion, a resilient coil engaged beneath said offset portion and having its ends bent outwardly beyond the strap and adapted to clamp an article therebetween, and a covering for said ends.

In witness whereof I have hereunto signed my name in the presence of two witnesses.

THOMAS DANIEL CARTER.
